UNITED STATES PATENT OFFICE.

RODERICK S. GOETZ AND EMIL S. RUDICH, OF NEW YORK, N. Y.

PROCESS OF AND APPARATUS FOR COLORING MEERSCHAUM.

1,412,858.

Specification of Letters Patent. Patented Apr. 18, 1922.

Application filed September 24, 1920. Serial No. 412,473.

To all whom it may concern:

Be it known that we, RODERICK S. GOETZ, a citizen of the United States, residing at New York, N. Y., and EMIL S. RUDICH, a subject 5 of the King of Roumania, residing at New York, N. Y., have invented new and useful Improvements in Processes of and Apparatus for Coloring Meerschaum, of which the following is a specification.

10 This invention relates to an improved process of and apparatus for coloring meerschaum, the principal object of the invention being to provide a process by means of which the color so much desired by smokers 15 is imparted to articles such as pipes, cigar and cigarette holders in a very short time, by subjecting the articles to the action of tobacco smoke both at the interior and exterior thereof, and without the use of any foreign 20 substance such as oil, varnish or the like.

A further object of the invention is to provide a suitable apparatus for carrying out the process above referred to.

With the foregoing and other objects in view, which will appear as the description proceeds, the invention consists in the novel process and features of construction of the apparatus which will be more fully described hereinafter, and particularly pointed 30 out in the claims.

The drawing accompanying and forming part of this specification illustrates in central vertical section a form of apparatus adapted for carrying out our improved 35 process.

Referring to the drawing, A designates a cylindrical member forming a chamber of sufficient size to permit the articles to be bodily placed therein. The member A is 40 preferably made of glass so that the action of the smoke on the articles may be readily observed without uncovering the chamber, although it is obvious that any suitable material may be used without departing from 45 the spirit and scope of this invention. The member A is formed at its lower end with a neck portion of smaller diameter than the body portion, in which neck is inserted a suitable removable stopper B, said stopper 50 having a centrally disposed opening in communication with the interior of the chamber, and in which opening is snugly fitted a stem D, the inner end of which projects a considerable distance above the inner surface 55 of the stopper, for a purpose to be here-

inafter explained. The chamber is closed at its upper end by a removable stopper C, which is preferably, although not necessarily, made of cork. The stopper C is provided near its periphery with an opening in 60 communication with the interior of the chamber, and in this opening is secured a bowl-shaped member E having a small opening or port e through its bottom communicating with the chamber in the member A. A suitable support I, preferably formed of a disc of reticulated material, such for instance as wire fabric, may be provided for supporting the articles to be colored, the disc being of sufficient size to permit its edge to be bent 65 at an angle so as to engage the inner surface of the chamber wall with sufficient friction to retain the support in place. In the drawing are shown two pipes and a cigar or cigarette holder supported on the support, one of 70 the pipes designated G and the holder H.

In carrying out the process, the articles to be colored are placed on the support I in any desired position and the chamber closed by placing the stopper C in the end of the chamber. The bowl E is then either filled with tobacco or a cigar or cigarette supported therein in the same manner as in an ordinary holder, it being understood that the bowl may be of any desired size, that is to 80 say, it may be large enough to hold a considerable quantity of tobacco, or it may be of a size small enough to snugly hold only a cigar or cigarette. Suction is then applied to the end F of the tube or stem D and a 85 lighted match applied to the contents of the bowl E, whereupon a large volume of smoke fills the chamber A and settles around and within the articles supported in said chamber. By maintaining sufficient suction 90 through the stem D to cause the chamber to be continuously filled with a cloud of smoke, the articles very quickly become thoroughly saturated and colored throughout 95 their entire thickness and at all points on 100 their surface.

We have discovered, after considerable experiments, that the best results are obtained by locating the bowl E near the periphery of the stopper, since when it is placed at 105 the center of the stopper, the smoke passes directly downward and out through the tube D, and therefore does not remain in the chamber long enough to accumulate a sufficient volume therein to color the articles, 110

particularly if such articles are placed near the edge of the support. By placing the bowl near the periphery of the stopper, however, the smoke is caused to swirl around within the chamber before being lead out through the tube D, and thus a large volume of smoke will always be in circulation in the chamber so long as sufficient suction is maintained to keep the material in the bowl E alight and supply fresh smoke to the chamber.

Owing to the fact that the tube D projects up above the stopper B, any condensation of vapor within the chamber will settle on the upper surface of the stopper B and cannot enter the tube D until the space between the upper end of the tube and the upper surface of the stopper is completely filled. The stopper B is removed from time to time and cleaned so as to prevent the condensation entering the tube D. The suction may be produced in the ordinary way, by the operator placing the end F of the tube in his mouth and sucking thereon, thus creating a vacuum in the chamber A and causing the smoke from the bowl E to enter the chamber. In this manner a smoker can enjoy the comfort derived from smoking the tobacco, while at the same time he is coloring his pipes, etc., for future use. On the other hand, for the purpose of commercially coloring the articles, regardless of the use of tobacco from the smoker's standpoint, some suitable form of vacuum-creating apparatus may be placed in communication with the tube D and the chamber A and its bowl may be of sufficient size to operate on a large number of articles at the same time. We have found that a smoker, by subjecting his pipe to the action of tobacco smoke in the manner hereinbefore described, while smoking only his customary quantity of tobacco, can within a couple of weeks impart to such articles a far more thorough and beautiful coloring than it was possible to do by even a year or more of smoking in the ordinary way.

Having thus described our invention, what we claim is:

50 1. The process of coloring articles of meerschaum, which consists in supporting such articles in a closed vessel and passing

a volume of tobacco smoke through said vessel in contact with such articles.

2. The process of coloring articles of meerschaum, which consists in supporting such articles in a closed vessel, creating a partial vacuum in said vessel, and causing tobacco smoke to enter the vessel in contact with such articles.

60 3. An apparatus for coloring articles of meerschaum, comprising a vessel, a tube in communication with said vessel, a bowl in communication with said vessel, and means for supporting the articles to be colored 65 within the vessel between such bowl and said tube.

4. An apparatus for coloring meerschaum, comprising a cylindrical vessel, a tube in communication with said vessel; a bowl in 70 communication with the vessel but eccentrically disposed with relation to the axis of the vessel, and means for supporting the meerschaum between said bowl and said tube.

75 5. An apparatus for coloring articles of meerschaum, comprising a cylindrical vessel provided at its opposite ends with removable stoppers, a suction tube passing through one of said stoppers into communication 80 with said vessel, and extending beyond said stopper, a bowl carried by the other stopper and in communication with said vessel, said bowl being eccentrically disposed with relation to the stopper, and means for supporting the articles within said vessel between 85 said bowl and tube.

6. An apparatus for coloring articles of meerschaum, comprising a cylindrical vessel provided at its opposite ends with removable 90 stoppers, a suction tube passing through one of said stoppers into communication with said vessel and extending beyond said stopper, a bowl carried by the other stopper and in communication with said vessel, said 95 bowl being eccentrically disposed with relation to the stopper, and means for supporting the articles within said vessel between said bowl and tube, said means comprising a reticulated member.

100 In testimony whereof we have signed our names to this specification.

RODERICK S. GOETZ.
EMIL S. RUDICH.
